UNITED STATES PATENT OFFICE

148,258

DESIGN FOR A CAN PIERCER

Gus P. Steen, Long Beach, Calif.

Application July 9, 1946, Serial No. 131,433

Term of patent 14 years

(Cl. D22—2)

To all whom it may concern:

Be it known that I, Gus P. Steen, a citizen of the United States, residing at Long Beach, in the county of Los Angeles and State of California, have invented a new, original, and ornamental Design for a Can Piercer, of which the following is a specification, reference being had to the accompanying drawing, forming part thereof.

Fig. 1 is a side elevational view of a can piercer, showing my new design;

Fig. 2 is an end elevation; and

Fig. 3 is a bottom view of the same.

I claim:

The ornamental design for a can piercer, as shown.

GUS P. STEEN.
